(57) **CLAIM**

The ornamental design for a boat motor cover, as shown and described.

DESCRIPTION

FIG. 1 is a perspective view of the boat motor cover;

FIG. 2 is a back view thereof;

FIG. 3 is a front view thereof;

FIG. 4 is a left view thereof;

FIG. 5 is a right view thereof;

FIG. 6 is a top view thereof;

FIG. 7 is a bottom view thereof; and,

FIG. 8 is an exploded perspective view of the boat motor cover.

The ornamental design, which is claimed, is shown in solid lines in the drawings. Any broken lines in the drawings are for illustrative purposes of the boat motor cover and form no part of the claimed design.
